UNITED STATES PATENT OFFICE.

SETH W. SHEPARD, OF LEOMINSTER, MASSACHUSETTS, ASSIGNOR TO THE HOWE COMB COMPANY, A CORPORATION OF MASSACHUSETTS.

FASTENING DEVICE FOR LADIES' HANDBAGS OR VANITY-CASES.

1,375,114.

Specification of Letters Patent. Patented Apr. 19, 1921.

Application filed October 14, 1920. Serial No. 416,983.

To all whom it may concern:

Be it known that I, SETH W. SHEPARD, a citizen of the United States, residing at Leominster, in the county of Worcester and 5 State of Massachusetts, have invented a new and useful Fastening Device for Ladies' Handbags or Vanity-Cases, of which the following is a specification.

This invention relates to a fastening device especially adapted for use for fastening a hinged cover to the body of the article to which it is applied, as for example, a lady's hand bag or vanity case.

The principal objects of the invention are 15 to provide a neat fastening device which will present no projecting points that are likely to catch or tear articles being placed in or removed from the bag or case, and to so construct it that it will securely hold the 20 cover even after long usage, will not mar it in any way, and will be simple and inexpensive.

Reference is to be had to the accompanying drawings, in which—

25 Figure 1 is a plan of a lady's hand bag cover showing a preferred embodiment of this invention applied thereto;

Fig. 2 is a side elevation of the same partly in section;

30 Fig. 3 is a central sectional view of a portion thereof on enlarged scale;

Fig. 4 is a similar view showing the locking device disengaged, and

Fig. 5 is a fragmentary plan of the cover.

35 The invention, although capable of use for other purposes, is shown as applied to a ring 10 constituting the top of a lady's hand bag and a cover 11 hinged thereto. These parts can conveniently be made of 40 celluloid or other suitable material. In the edge of the ring 10 at a point opposite the hinge is a depression below its surface in which is freely pivoted a shank 12. This is shown in the form of an ordinary brass pin 45 having a head 13 and provided with a flattened end which is perforated for the reception of the pivot pin. This pivot pin is shown in the form of a wire 9 extending inside the cover and having its ends looped 50 together. The shank 12 extends inside a globular member 14 and is provided with a spring 15 inside bearing on the bottom or enlarged end of the member 14 and on the underside of the head of the shank or

pin 12. This holds the globular member 14 55 resiliently in position.

This member 14 is shown as made of two substantially hemispherical parts having their edges located directly opposite each other and cemented to a flat ring 17. All 60 these parts may be made of celluloid. It will be seen that this holding member has a smooth convex lower surface.

In manufacture, the pin 12 is put into the lower half of the globular member with 65 the spring underneath the head. The central ring and the other half of the globular member are cemented in position. Then the point is flattened and the perforation provided. The wire 9 is inserted and fixed in 70 position.

The cover 11 is provided with an open edged perforation or slot, 20 therethrough which is counter-sunk at 21 to receive the lower smooth convex surface of the holding 75 member 14. When the cover is closed the globular member 14 is turned upwardly from the position shown in Fig. 4. The shank is made of just sufficient length so that when the globular member is forced up 80 and slides over the edge of the perforation 20 the spring will have to be compressed in order to allow it to pass over. It is pushed over this point into the counter-sunk end of the perforation and the spring is left under 85 compression. To disengage it, it is necessary to compress the spring still further in order to get the member 14 out of the counter-sunk depression. Therefore, this holds the 90 cover firmly in position and there is practically no danger of its being opened accidentally. At the same time the parts are disengaged in the simplest possible manner merely by pushing the member 14 over to the left in Fig. 3, so that it swings into the 95 position shown in Fig. 4. It will be seen, therefore, that this is a very simple and attractive fastening device and one that avoids the usual objection to those which have been used, namely, the presence of projecting angles and points.

100 Although I have illustrated and described only one form of the invention and shown it as applied to one article only, I am aware of the fact that modifications may be made in 105 the fastening device and that it can be applied to vanity cases and various other articles without departing from the scope of

the invention as expressed in the claims. Therefore I do not wish to be limited to all the details of construction herein shown and described or to the particular article illustrated, but what I do claim is:—

1. The combination with the top of a hand bag and a cover hinged thereto and in contact therewith throughout its top surface, said top having a depression in its edge 10 opposite the hinge, of a pivoted fastening device therefor comprising a freely swinging shank pivoted in said depression in the top, with a smooth surfaced globular holding member mounted thereon, said cover 15 having an open-ended slot having a depression for receiving said holding member.
2. The combination with the annular top of a hand bag having a notch therein, and a flat cover pivoted thereto, of a fastening 20 device comprising a shank pivoted on the bottom of the notch and having an enlarged end yieldingly mounted thereon, a wire extending from said notch through the wall of said hand bag top for securing the lower end 25 of said shank, said cover having an open-ended slot extending therethrough for receiving the shank sidewise, said shank having a head, and a spring under the head of

the shank in position to hold the enlarged end yieldingly.

3. In a fastening device for the purpose described, the combination of a pivoted shank having a head at the end remote from the pivot, a hollow globular member slidably mounted on said shank, and a spring inside 35 the globular member bearing on its bottom and on the under side of the head of the shank, said globular member comprising similar hollow hemispherical members, and a central circular flat plate on the opposite 40 sides of which they are cemented, said plate having a central perforation for said shank.

4. In a fastening device for the purpose described, the combination of a pivoted shank and a head at the end remote from the 45 pivot constituting a hollow globular member mounted on said shank, said globular head comprising two similar hollow hemispherical members, and a central circular flat plate on the opposite sides of which they are 50 cemented, said plate and one of the hemispherical members having a central perforation for said shank.

In testimony whereof I have hereunto affixed my signature.

SETH W. SHEPARD
